UNITED STATES PATENT OFFICE.

ROGER W. CLIFFORD, OF SCHENECTADY, NEW YORK

THROTTLE VALVE.

Application filed February 3, 1928. Serial No. 251,537

This invention relates to throttle valves of the single poppet type, an instance of which is exemplified in Letters Patent of the United States No. 1,338,489, granted and issued to Roger W. Clifford and Philip J. Nichols, under date of April 27, 1920, upon which this invention is an improvement. The object of the present invention is to provide simple, inexpensive and readily applicable means whereby the supply of motive fluid controlled by a throttle valve of the type above specified, may be more perfectly graduated in its opening movement than has heretofore been practicable.

The improvement claimed is hereinafter fully set forth.

In ordinary practice, it frequently occurs that in starting a heavy train, the driving wheels of the locomotive will be slipped, by reason of the engineer moving the throttle lever so as to effect too sudden an admission of steam, and in too great a volume, to the cylinders. In starting lighter trains, sudden shocks on the draft gears are produced. These objections are obviated by the present invention, in the practice of which, in the preliminary stages of the unseating movement of the valve, its area of delivery opening is, at first, slight, after which steam delivery is continued, briefly, without increase of delivery opening, and thereafter, the area of the delivery opening is progressively increased to the maximum afforded by the limit of lift of the valve.

In the accompanying drawing: Figure 1 is a plan view of a throttle valve appliance, illustrating an embodiment of the invention, the valve being removed in the upper half of the Figure; and, Fig. 2, a vertical transverse section, on the line *a a* of Fig. 1.

In the practice of the invention, referring descriptively to the specific embodiment thereof which is herein exemplified, an open topped, and open bottomed hood or casing, 1, is, as in Patent No. 1,338,489 aforesaid, located at the top of the stand pipe, 2, through which steam passes from the boiler to the cylinders of a locomotive or other steam engine, being, in this instance, formed integral with said pipe. A beveled or conical valve seat, 1^b, is machined at, or near, the bottom of the casing, 1, and vertical guiding ribs, 1^c, are formed on the inner side of the wall thereof.

A cylindrical throttle valve, 3, of the poppet type, which is bored out truly on its inner surface, and provided, at its bottom, with a bevelled face, 3^d, is adapted to be seated on the valve seat, 1^b, and thereby to control the passage of steam through the casing, from the boiler to the stand pipe. The throttle valve is raised and lowered, from and to its seat, by connections to any suitable known valve operating mechanism, which does not, in and of itself, form part of the present invention, and is not, therefore, herein set forth. The valve operating mechanism is connected to a cross head, 5, which is coupled, by a pin, 5^a, to lugs on the upper end of a valve stem, 6, connected, with the capacity of a limited degree of relative vertical movement, to the throttle valve, 3. The throttle valve is guided, in its movements, from and towards its seat, by the ribs, 1^c, on the casing, against which a flange, 3^a, formed on the periphery of the throttle valve, closely adjacent to the valve face, 3^d, and having a cylindrical face, bears. The bore of the portion of the casing, 1, which surrounds the flange, 3^a, is made of slightly greater diameter than said flange, and a narrow steam delivery space, 1^d, is thereby presented between the flange and the casing, during the preliminary portions of the unseating movement of the throttle valve.

The valve stem, 6, carries a pilot valve, 8, seating in a cover plate, 3^b, which closes the top of the throttle valve, and is secured removably thereto by bolts, 3^c, and nuts. A properly packed balancing piston, 7, is fitted, with the capacity of relative vertical movement, in the throttle valve.

The pilot valve and balancing piston operate similarly to the corresponding members of the appliance of Patent No. 1,338,489, and as said members do not, in and of themselves, form part of the present invention, said operation is not herein set forth.

In the operation of the invention, when unseating movement is first imparted to the throttle valve, the steam delivery opening exposed by such movement is limited to the narrow annular steam delivery space, 1^d, between the periphery of the flange, 3^a, and the wall of the casing, 1, and this restricted delivery opening does not begin to be increased, in the further lift of the valve, until the bottom of the flange, 3^a, passes the top of the bore of the casing which surrounded it in its preceding upward traverse. Thereafter, in the continued unseating movement, a progressively increasing opening for steam

delivery is uncovered, until the maximum which is afforded by the limit of lift of the throttle valve, is attained. It will be obvious that the limit of degree of preliminary 5 steam admission which is resultant on the described construction, and mode of operation, effectually prevents the detrimental results of the undue suddenness of admission which frequently is practiced in the operation of the throttle valves of present practice.

What is claimed as new and desired to be secured by Letters Patent is:

In an appliance for controlling the flow 15 of motive fluid, the combination of a throt-

tle valve of the poppet type, having a lower seating face and a peripheral flange above and adjacent thereto; means for unseating and seating said valve; and an open topped casing, having a valve seat, a plurality of 20 guiding ribs, projecting inwardly, on which the valve flange is adapted to bear, and a bore, of greater diameter than the valve flange, said bore being interposed between the valve seat and the guiding ribs, thereby 25 presenting a restricted opening for fluid delivery, in the preliminary stage of the unseating movement of the valve.

ROGER W. CLIFFORD.
